8 Claims

ABSTRACT OF THE DISCLOSURE

A wooden scaffold horse made in several readily assembled and disassembled parts each being constructed to cooperate when in both knocked down and set-up position of parts whereby to form a more secure and symmetrical package for both handling and shipment and a more rigid load supporting horse with the minimum of time and labor.

BACKGROUND OF INVENTION

The general combination and arrangement of most parts is similar to that shown and described in my Pats. 3,103,988 of Sept. 17, 1963 and 3,379,282 of Apr. 23, 1968, the primary difference being in the manner and means whereby the parts are connected and associated for a more rigid and less time consuming assembly in both knocked down and set-up assembled position of parts.

THE INVENTION

The invention is primarily concerned with the manner and means whereby a more rigid assembly of the several necessary parts is effected with a minimum of effort and time and produces a better shaped package for both handling shipment as well as one which may be repeatedly set up for use and knocked down without difficulty of sticking parts usually resulting in damage from the use of wooden dowel securing means between parts. A further advantage results from the means whereby the collapsed interconnected leg members are automatically secured, when packed, and forced apart when unpacked and lifted from the work plank where packaged, permitting the leg units to be quickly slid to a required adjusted position under light clamping action on the parallel work plank edges for final securing with only light additional added pressure.

A primary object of my improved scaffold horse is to provide a single means which serves both as a stop and also as a fastener for the wider ends of said tapered leg member units, said leg units being further provided with slots at opposite ends which extend inward from the ends thereof to receive therein a rigid securing means which projects upwardly from the underside of said work plank, certain of which supports the folded leg member units in packaged position and which leg units support the plank in set-up working position.

A further object concerns the twistable fastener means which passes into and through the registering slots in the smaller or narrower end of each tapered leg member units whereby to cooperate with spring-action spreader and the rigid fastener members to align position and hold said leg units on said plank without rattle or movement, said twistable fastener means also being adapted when twisted to engage the outer surface of said leg units to cooperate with said spring acting spreader to secure said units to said plank and to pass through said slot to forceably release said units from said plank.

A still further object of my improved scaffold horse provides spring hinge means connecting the spreader means at the inner side of one leg member of each pair of leg units whereby the spreader means or board will parallel both interconnected leg members and be sand-

2

wiched in-between them as shown in FIG. 6 when the parts are packaged, said parts serving to exert force to spread said leg members of each unit when separated from said plant and to interengage with the leg member opposite the one to which it is secured to forceably lock said leg members to said plank in the desired set-up position of parts.

Other objects and advantages of my improved scaffold horse will be appreciated as the description continues with reference to the accompanying drawings wherein:

FIG. 1 shows in perspective the invention in set-up position of parts;

FIG. 2 is a section taken on line 2—2 of FIG. 1 showing the parts somewhat enlarged;

FIG. 3 is an exploded view of the package showing the parts thereof in their folded position;

FIG. 4 is a view taken on line 4—4 of FIG. 2;

FIG. 5 is a side edge view of the parts folded in package forming and handling position ready for wrapping and shipment as required;

FIG. 6 is a longitudinal section view through one pair of the folded interconnected leg units and attached intermediate spreader strut showing these parts ready for shipment but removed from the packaged position of parts of FIG. 5;

FIG. 7 is a fragmental sectional view of a part of one leg element and attached spreader showing the spring hinge connecting the two;

FIG. 8 is another fragmental view with the parts broken

30 and in section to show the bifurcated end of the spreader strut and the spring wire coiled about the pintle rod with the ends thereof bent at right angles and anchored into the inner face of one of the leg members;

FIG. 9 is an end view of interconnected legs of FIG. 6 35 in automatic expanded set-up position of parts showing the positions to which the strut may assume at such times;

FIG. 10 is an end perspective view of the leg parts when in the position of FIG. 9 and prior to fixed clamping with the side edges of the work plank;

40 FIG. 11 is an end perspective view of the parts when in the folded position of FIG. 6; and

FIG. 12 is a view taken on the line 12—12 of FIG. 3.

In accordance with the invention the two pair of interconnected tapered legs are each formed with slots 45 at opposite ends thereof as best shown in FIGS. 10 and 11. Retaining members in the form of nail-type fasteners two of which have modified relatively rotatable right angularly turned heads so as to pass through the registering slots at the smaller end of each pair of tapered leg member openings and driven into the plank to form the package. After this it is only necessary to lift that end of the leg member relative to the plank under the securing means and slide it toward the opposite end of the plank to release the larger end of said pair of legs from under the flat base heads of the rigid combined fastener and stop elements.

As shown in FIG. 1 of the drawings the horse comprises a work supporting plank 2 having interconnected leg pairs or units 4, 6 and 8, 10 clampingly embracing the side edges of the plank 2 adjacent opposite ends thereof. The maximum width of each leg member is substantially equal to the width of the top board or work plank 2. The edges of the plank are grooved, as at 12, 14 to slidably receive the wide end of the leg units during assembly. When each pair of interconnected legs 4, 6 and 8, 10 are spread and slid into the final position of FIG. 1 the spreader strut members 16 are then swung up and forced into position against the cross strips 18 secured to the legs in any suitable manner such as by nails or glue. Each leg member has groove 20 intersected by a well 22 into which the ends of the bails 24 are seated.

The interconnecting bails 24 are formed as an open wire loop having free ends 26, 28 provided with lateral extensions fitting into the wells 22 all as will be readily understood.

Each of the leg units 4, 6 and 8, 10 is provided with notches at the corners 30, 32 providing abutments for the angle bent parts of the bails 24. A flexible strap 34 is secured at each of its ends to a leg to hold captive the bail whose bent end is pivoted in the well 22 in the opposite leg member of each leg pair. Each leg is also provided at each end with registering open ended slots 36 for snugly receiving the vertical shaft of headed nail-like fasteners. As shown in FIG. 3 the nail-like leg fastener 38 also functions as a stop for the leg units, is secured adjacent the opposite ends of the work supporting plank 2 for movement into the slot 36 at the wide end of the legs when packaging. Each said end fastener 38 is formed with a rounded disc-like head 40 that is much larger than the slot so as to bear on the outer surface of the legs 6 and 10 on each side of the slot to securely retain the leg units when packaged on the under face of the plank 2. Fasteners 42 are also mounted in each side of the center of the plank and extend up through the registering slots in the narrow ends of the leg units to rigidly retain that narrow end of each of said units in contact with the plank. Each said fastener 42 is formed with a shaft 44 which has a screw threaded lower end not shown which is fastened in the plank and a right angularly bent over upper end which permits twisting of the fastener by hand from a position over the slot to a position over the top surface of the outer leg members whereby the smaller end of the leg units 4, 6 and 8, 10 are retained in fixed bearing contact with the under surface of the plank for further packaging. To thereafter release these units it is only necessary to twist or turn the bent over end to a position over the slot 42 through which it may pass, in which the units may then be moved up free of the fastener 42 and its head 44 as illustrated in FIG. 3.

As leg members 4 and 10 of each unit are provided with an inverted U-shaped staple 46 and each spreader board member 16 is formed with a longitudinal slot 48 shown in FIGS. 2 and 3 to receive these staples 46 when the parts are to be packaged. A band 50 is passed across these spreaders and fitted into a slot formed in legs 4, 8 and a similar slot in the spreader member 16 to retain the member against the leg.

In forming the package fasteners elements 38 and 42 may be driven or secured into the plank in the positions illustrated in FIG. 3 with the heads 40 and legs 44 spaced from the under surface of the plank an amount equal to the thickness of the leg units, plus the thickness of strips 18, plus an amount to receive straps 34 and the bails. For shipping the legs are collapsed as shown at 8, 10 in FIG. 3 and the open ended slots 36 are pushed under the head 40 of fasteners 38. At this position of parts the slots 36 in the narrow ends of the leg units will drop over the bent parallel fastener heads 44. The fastener heads 44 are then twisted to locking position over the legs 6 and 10. The package can obviously be unassembled by merely twisting the fastener heads 44 to parallel the unit slots 36. This frees narrow end of each leg unit for upward movement over the fasteners 42 and then for lateral movement from under heads 40. The fasteners need not be positioned with close tolerances in order to assemble and retain the parts since the lateral dimensions of heads 40 and legs 44 allow great freedom in positioning of the fasteners. If desired, the fasteners may be driven through the slots and into the plank to assemble the package. This mode of assembly permits the fasteners to be driven close to the bottom of the slots.

In FIGS. 6 to 11 a modified form of spreader strut 16' is shown, said strut comprises a generally rectangular board which as shown in FIGS. 1 to 5, the primary difference being the means 65' for fixedly connecting this strut to the inner side of leg members 4 and 8 by the pivotal

rod best shown in FIGS. 7 and 8. This mounting of the struts 16' at their bored bifurcated end permits them to be sandwiched in-between the superimposed leg members as shown in FIG. 6. The use of the slot can thus be illuminated in the strut bodies, as the hinge thus provided will hold the struts aligned with the adjacent opposing sides of the folded legs of each unit when packaged. On the opposing, central inner faces of the leg units as shown as 63' FIGS. 6 and 10 is shown a vertical series of spaced grooves 63' into which the free end of the strut 16' is adapted to seat when forced out automatically by a spring steel wire 62' coiled about the pintle 65' between the extended side ends 61' of the strut 16'. In order to automatically exert lifting force upon the structure as they are lifted from their packaged condition one end of the coiled wire 62' is rested upon the inner face of the leg 4' and the opposite end thereof upon the angled surface of the strut between the spaced extended ends 61'. As shown in FIG. 8 the remote ends of the pintle rod 65' beyond the sides of the bored strut ends are turned at substantial right angles and the ends thereof are driven or otherwise attached rigidly to the adjacent leg. It will thus be seen that the strut will automatically position itself horizontally between the legs of each unit as the leg units are spread in the act of releasing them from packaged condition so that it is only necessary thereafter to place the side edges of the work plank 2 between the spaced wide ends of the interconnected legs and slide them to the desired points thereon whereupon a firm force is applied to the underside of the strut to advance the free end thereof into the next groove of the series 63' to finally fix all parts for use.

I claim:

1. A knockdown scaffold horse comprising an elongated rectangular work plank, two pairs of hingedly interconnected superimposed leg members, spring acting spreader means between each pair of said leg members, registering slots extending outwardly from opposite ends of the leg members of each pair and means projecting from one side of said plank and entering the registering slots of each pair and operative to retain said leg members on said plank against the action of said spreader means.

2. The structure of claim 1 in which certain of said securing means are twistable to engage one of said leg members adjacent one of said slots and secure said leg member substantially parallel with the other of said pair of leg members and said intermediate spreader means.

3. The structure of claim 1 in which certain of said securing means have heads which are twistable to a position parallel with its registering slot whereby to pass therethrough and release said pairs of leg members from said work plank.

4. The structure of claim 1 in which said spring acting spreader means is automatically operative to space the leg members of each pair and cause one end thereof to clamp upon the side edges of said plank.

5. A knockdown scaffold horse comprising an elongated rectangular work plank, two pairs of hingedly interconnected, superposed leg members, spring acting spreader means mounted intermediate each pair of said leg members, registering slots extending inward from the opposite ends of the leg members of each pair and securing means projecting from one side of said plank and through said slots to engage the uppermost leg member of each said pair to retain same on said plank against the action of said spreader means.

6. A scaffold horse package comprising a rectangular plank, a pair of similar tapered legs supported one on the other and having at the wider ends thereof the plank with the maximum width of the legs adjacent said one end and being substantially equal to the width of the plank, a similar pair of legs similarly supported adjacent the other end of the plank, said pairs being positioned adjacent each other, a slot extending into the wide end of each

pair of legs, and fasteners secured in the plank and extending through the slot, each fastener having a head portion adapted to overlie the outermost leg member adjacent the slot.

7. The structure of claim 6 in which a slot extends into the narrower ends of each pair of legs, and twistable fasteners secured in the plank and extending through said last-mentioned slots.

8. The structure of claim 7 in which resilient means 10 exert pressure on a member between each pair of legs, a slot extending into the narrow end of each said pair of

legs, and twistable fasteners secured in the plank and extending through said last-mentioned slot.
